Fig. 6

FIGURE 1 is a front elevational view of a gasoline dispensing unit showing my new design and which includes a canopy.

FIGURE 2 is an end elevation viewed from the left of FIGURE 1.

FIGURE 3 is an end elevation viewed from the right of FIGURE 1.

FIGURE 4 is a front elevational view of a modified form of the gasoline dispensing unit showing my new design in which the canopy is omitted.

FIGURE 5 is an end elevation viewed from the left of FIGURE 4.

FIGURE 6 is an end elevation viewed from the right of FIGURE 4.

The rear elevations of the units shown in FIGURES 1 and 4 are substantially the same as the respective front elevations shown in FIGURES 1 and 4.

The essential features of the design reside in the solid line portions.

This application is a continuation-in-part application of my copending applications Serial Numbers D.66,369 and D.66,370 both of which were filed on August 16, 1961 and which have become abandoned since the filing of this application.

I claim:

The ornamental design for a gasoline dispensing unit, as shown and described.
